UNITED STATES PATENT OFFICE.

GEORGE W. JOHNSTON, OF SAND SPRINGS, OKLAHOMA.

BOAT-PROPELLING MECHANISM.

Application filed September 9, 1926. Serial No. 134,414.

The present invention relates to apparatus for propelling water craft, and aims to provide a novel form of boat propelling means making use of air motor appliances operative both for actuating the boat in a forward direction and also for producing a boat retarding action as required for slowing down and stopping or reversing the boat's movement.

10 In carrying out this object of the invention, I have devised a construction and arrangement of air motor mechanism, employing air motors of the duplex type, and including pump mechanism operative for 15 helping to maintain a supply of air under pressure for the use of the motors. In this connection I have also devised suitable means for exploding hydrocarbons with a view to assisting in maintaining the gas 20 pressure supply and reinforcing the same as the gas under pressure is fed to the various air motors.

The invention further comprises apparatus in which is included means adapted to 25 be actuated by the water current for operating air compressing means, and also having provision for utilizing this current-actuated means for aiding in the propulsion of the boat under certain circumstances.

30 With the foregoing general objects in view, the invention will now be described by reference to the accompanying drawings illustrating one preferred form of construction, as well as a modified form of construction, which I have devised for embodying 35 the proposed improvements, after which the several features and combinations deemed to be novel will be particularly set forth and claimed.

40 In the drawings—

Figure 1 is a side elevation, partly broken away, illustrating a boat equipped with propelling apparatus constructed in accordance with the present invention;

45 Figure 2 is a plan view of the same, also partly broken away;

Figure 3 is an enlarged sectional detail view, showing a portion of the high pressure cylinders with its gas heating connection and ignition device;

50 Figure 4 is a horizontal sectional view of the same, representing a section on the line IV-IV of Figure 3;

Figure 5 is a diagrammatic view illus-

trating the electrical circuit and circuit closing device of the ignition means for the high pressure cylinder;

Figure 6 is an elevation, showing a face view of one of the propeller elements;

Figure 7 is a section taken on the line 60 VII-VII of Figure 6;

Figure 8 is a side elevation, similar to Figure 1, but illustrating a modified form of construction and arrangement of the propelling mechanism and apparatus for maintaining the air pressure supply;

Figure 9 is a plan view of the same; and

Figure 10 is an enlarged vertical sectional view of the clutch and governor device employed in the modified form of construction.

Referring now to the drawings in detail, these illustrate the improved apparatus in operative relation to the hull 12 of the boat in the bow of which is formed a compressed air supply tank 13 equipped with a safety valve 14, as shown in Figures 1 and 2. For maintaining a supply of compressed air within the tank 13, I employ an air compressing means substantially of the type illustrated in Patent 1,360,222, issued to me on November 23, 1920, and comprising collapsible propelling members 15 carried by a vertical shaft extending centrally through the compressor casing 16 which is connected by a pipe 17 with the tank 13 and also with an exhaust pipe 18 controlled by a valve 19. In the shaft between the propeller members 15 and compressor casing 16 may be arranged a suitable clutch device 20 and 80 an operating handle 21. The propeller members 15 are of course mounted beneath the hull of the boat, and are preferably enclosed in suitable screen work 22 to prevent the entry of any foreign matter which might clog the action of the propellers.

85 Mounted in suitable bearing brackets 25 secured to the bottom of the hull 12 are reciprocating propeller shafts 26 and 26', each of which is provided with one or more propeller members comprising a vertical frame 27 having a series of shutter elements 28 mounted on horizontal pivots 29, as clearly illustrated in Figures 6 and 7. The propeller members thus described are mounted 90 on the side shafts 26 so as to face in a rearward direction, while the propeller member carried by the shaft 26' is mounted to

face in the opposite or forward direction, whereby, since the shutter elements 28 are automatically closed by the force of water pressure and automatically opened on moving in a direction opposite to that in which the propeller members face, the propeller shafts 26 act to propel the boat in a forward direction, and the shaft 26' effects a slowing down of the boat's movement or a stopping or reversing of its movement altogether.

Each of the shafts 26 and 26' is connected by a link 30 with a vertically arranged lever 31 operating about a pivot 32 within the hull of the boat, as shown in Figure 1. The upper end of each of the levers 31 is provided with a sliding pivotal connection, indicated at 33, with the reciprocating plunger rod 34 of a duplex air motor cylinder 35 of the same character as covered by my application for patent Serial No. 494,804, filed August 24, 1921. Each of the air motor cylinders 35 is provided with an outlet connection 36 with the jacket 37' of a suitable high pressure cylinder 37, the latter having a safety valve 38 and also a release or exhaust outlet pipe 39 leading to the stern of the boat. Each of the air motor cylinders 35 is also provided with an intake connection 40 connecting with the high pressure cylinder 37, and having also a valve 41 controlling each of said connections 40.

I also provide a tank 42 for maintaining a supply of suitable hydrocarbon, such as gasoline, to be fed through a pipe 43 into the high pressure cylinder 37 by way of the Y-passage 44, for ignition purposes to reinforce the pressure within said cylinder. Referring more particularly to Figures 3 and 4, the pipe 43 connects with a suitable valve 45 operated by a ratchet gear 46 which is engaged by a pawl 47 fitted with a spring 48 and operating through the yoke 49 associated with the stem 50 of said valve 45. The stem 50 also carries an arm 51 adapted intermittently to close a pair of contacts 52 included in an ignition circuit 53 (see Figure 5) and thereby intermittently producing a spark at the spark plug 54 fitted through the wall of said cylinder 37. The pawl 47 is pivotally connected, as indicated at 56 to the plunger rod 34 of the intermediate air motor cylinder 35 or the one which actuates the propeller shaft 26'.

The plunger rod 34 of said intermediate cylinder 35 is also operatively connected with a single acting pump or compressor 60 provided with an intake pipe 61 connected with the compressed air supply tank 13, and also with an outlet pipe connection 62 leading to the high pressure tank 37. By this means the compressed air from the tank 13 is, by the action of said intermediate air motor cylinder 35 and the pump or compressor 60, stepped up in pressure on its way to the

cylinder 37 from which the supply is taken directly to the air motors 35.

The operation of the propelling mechanism will doubtless be clear from the foregoing in the light of the drawings, but may be briefly stated as follows. A supply of air under pressure is maintained in the tank 13 by the action of the pump or compressor 60 as operated by the folding blades 15 as actuated by the stream current, either 75 the normal current flow or that resulting from the movement of the vessel. This flow of compressed air is conducted to the high pressure cylinder 37 by way of the pump 60, and utilized for driving the air motors 35, and thereby actuating the propeller shafts 26 and 26', a valve 65 being provided in the pipe 61 for manually controlling the compressed air supply to the pump 60. The 80 air pressure is kept up by the action of the cylinder 60, driven from the intermediate air motor cylinder 35, and the pressure within the cylinder 37 is further maintained and increased by the intermittent explosion of the hydrocarbon charges fed thereto, from the cylinder 42, as above explained. A forward propulsion of the boat is thus effected, by the reciprocation of the propeller shafts 26, and the boat's movement steered by the usual form of rudder 67. Normally, the propeller shaft 26' is rendered inoperative, in the forward movement of the boat, by removing the pin 33 at the upper end of the corresponding lever 31 whereby said propeller shaft 26' is actuated, and in case the operation of said shaft 26' and its propeller member is required, the pin 33 is restored for connecting said propeller shaft for operation by the plunger rod 34 of said intermediate air motor cylinder 35, during 95 which operation the valves 41 connecting the cylinder 37 with the other air motor cylinder 35 are closed, thereby rendering the propeller shafts 26 inoperative.

In Figures 8 to 10 I illustrate a modified 100 form of construction, in which the air pump or compressor 60 is operated by propeller blades 15 as before, for maintaining the supply of compressed air within the tank 13. Besides the clutch 20 and clutch 105 operating handle 21', however, the operating shaft 70 of the propeller blades is equipped with a sprocket wheel 71 for driving a sprocket chain 72 which operates around a much smaller clutch sprocket wheel 73 115 journaled on a shaft 74 to which is keyed a clutch sleeve 75 provided with a common form of governor device indicated generally by the reference numeral 76 and adapted to be manually operated by means of a 120 clutch lever 77, all as clearly shown in Figures 8 and 10. The lower end of the shaft 74 carries a bevel gear 80 meshing with a bevel pinion 81 on the forward end 125 of a propeller shaft 82 carried in bearing 130

brackets 83 and fitted at its rear end with a rotary propeller member 85, as shown in Figure 8.

The remainder of the propeller mechanism in this modified form of construction is substantially the same as already described in the other views of the drawings, for utilizing the compressed air supply from the tank 13. In this modified form, the driving action provided between the pump or compressor 16 and its propeller members or blades 15, enables any excess driving action from the current flow to be employed for actuating the propeller 85 to drive the boat in a forward direction, for which purpose I simply operate the clutch lever 21 for operatively connecting the sprocket wheel 71 with the shaft 70 in an obvious manner. The remaining elements of this form of the construction operate in all respects the same as in the embodiment of the invention already described.

It will thus be apparent that I have devised a simple and practical form of construction for carrying out the desired objects of the invention, in which connection it may be stated that the air pump or compressor 16 is maintained in operation by its propeller blades through any forward movement of the boat or simply by the action of the current flow whenever the boat is moored with said blades submerged in the midst of a current.

While I have illustrated and described what I regard as the preferred form of embodiment of the invention, I desire to reserve the right to make such changes as may fairly fall within the scope of the appended claims.

What I claim is:

1. Boat propelling means comprising reciprocating propeller members, duplex air motors for actuating said propeller members, a compressed air tank for maintaining a compressed air supply for said motors, an air pump or compressor connected with said tank, and current actuated means for operating said air pump or compressor.

2. Boat propelling means comprising reciprocating propeller members for imparting either forward or rearward movement to the boat, duplex air motors for actuating said propeller members, a compressed air tank for maintaining a compressed air supply for said motors, an air pump or compressor connected with said tank, and cur-

rent actuated means for operating said air pump or compressor.

3. Boat propelling means comprising reciprocating propeller members, duplex air motors for actuating said propeller members, a compressed air supply tank, a high pressure tank intermediate said supply tank and motors, and a pump actuated by one of said motors for stepping up the pressure between said supply tank and high pressure tank.

4. Boat propelling means comprising reciprocating propeller members, duplex air motors for actuating said propeller members, a compressed air supply tank, a high pressure tank intermediate said supply tank and motors, and means for intermittently firing a charge of hydrocarbon compound within said high pressure cylinder.

5. Boat propelling means comprising reciprocating propeller members, duplex air motors for actuating said propeller members, a compressed air supply tank, a high pressure tank intermediate said supply tank and motors, means for intermittently supplying a charge of hydrocarbon compound to said high pressure cylinder, and means operating in timed relation to said first intermittent means for igniting said hydrocarbon compound.

6. Boat propelling means comprising reciprocating propeller members, duplex air motors for actuating said propeller members, a compressed air supply tank, a high pressure tank intermediate said supply tank and motors, valve means actuated by one of said motors for feeding a charge of hydrocarbon compound to said high pressure cylinder, and means operating in timed relation to said valve means for igniting said hydrocarbon compound.

7. Boat propelling means comprising reciprocating propeller members and air motors for actuating the same, a compressed air tank for maintaining a compressed air supply for said motors, an air pump or compressor connected with said tank and provided with current actuated means for operating said pump or compressor, a rotary propeller provided with a drive connection from said current actuated means, and means for disconnecting said drive connection.

In witness whereof I hereunto affix my signature.

GEORGE W. JOHNSTON.
